DETACHABLE DISPENSER FOR BOTTLES,
WITH PLUNGER-ACTUATED RECIPRO-
CATING VALVE

Carl F. Anderson, St. Paul, Minn.

Application November 23, 1945, Serial No. 630,333

5 Claims. (Cl. 222—385)

1

This invention has relation to a dispenser adapted to be attached to a bottle, or other receptacle, containing a liquid substance, such as catsup, mustard, dressing, etc., to be removed from the bottle or receptacle in measured quantities.

An object of the invention is to provide a device for dispensing measured amounts of a liquid substance from a bottle or other container having the liquid substance which will be of simple, inexpensive, novel and improved construction.

A further object is to provide a liquid substance dispensing device of the character as stated wherein will be incorporated several desirable and improved features and characteristics of construction which will be novel both as individual entities of the liquid substance dispensing device and in combination with each other.

And a further object is to provide a device for dispensing liquid substances which will include features and characteristics of construction as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification,

Fig. 1 is a central longitudinal sectional view of a dispenser made according to the invention, the view also disclosing, in section, a bottle with which the dispenser is associated;

Fig. 2 is a central longitudinal sectional view of the dispenser agreeing with the disclosure of Fig. 1 but showing operative parts of said dispenser in different positions;

Figs. 3 and 4 are central longitudinal sectional views of the dispenser agreeing with the disclosures of Figs. 1 and 2 but showing operative parts of said dispenser in still other different positions;

Fig. 5 is an elevational view of a pump plunger of the dispenser as when removed from the remainder of said dispenser; and

Fig. 6 is an elevational view, partially in section and partially broken away, of a hollow slide valve or sleeve of the dispenser as when removed from the remainder of said dispenser.

2

A stationary hollow casing or cap member of the new and improved dispenser is denoted 10. While said stationary hollow casing or cap member 10 could be otherwise constructed, it is in the disclosure as made of an integral mass of plastic material.

A body portion 11 of the hollow casing or cap member 10 is of general cylindrical configuration and includes an annular flange or skirt portion 12 at its periphery having an internal thread 13 adapted to be turned down upon an external thread 14 on the mouth or neck of a bottle or other container, such, for example, as the bottle indicated 15.

An extension portion 16 of said hollow casing or cap member 10 also is of general cylindrical configuration as disclosed. More explicitly, said extension portion 16 is constituted as an elongated member which is integral with and extends outwardly or downwardly from a central part of the body portion 11 in spaced, substantially concentric relation to the annular flange or skirt portion 12. Desirably, the construction and arrangement will be such that when the dispenser is applied to a bottle or other container the outer or lower end of the extension portion 16 of said dispenser will be situated in proximate or adjacent relation to the bottom wall of said bottle or container and the exterior side surface or surfaces of said extension portion 16 will be situated in spaced relation to the side wall or walls of the bottle or container, about as disclosed in Fig. 1 of the drawing.

An elongated pump chamber 17 of the stationary hollow casing or cap member 10, cylindrical as disclosed, is defined at its outer or lower end by a transverse closure well 18 at the end of the extension portion 16 spaced from the body portion 11 and at its circumference by an internal cylindrical wall 19 of said extension portion. A concavity 20, of cylindrical configuration as disclosed, in the outer or upper surface of the body portion 11 is in surrounding relation to the inner or upper end of the elongated pump chamber 17, and said elongated pump chamber is continuous from the location of said concavity 20 to said transverse closure wall 18. A base wall 21 of the body portion 11, defining the base of the concavity 20, is in surrounding relation to the inner or upper end of the pump chamber 17 and as shown is in perpendicular relation to the longitudinal axis of the extension portion 16. An outer or lower inlet port 22 in an outer or lower part of the cylindrical wall of said extension portion 16, adjacent the transverse closure wall

18, is for affording communication between the interior space of a bottle or container, such as 15, upon which the dispenser is located and the outer or lower end portion of the pump chamber 17, and a discharge outlet 23, through the extension portion 16 and the body portion 11 leads away from said pump chamber by way of an inner or upper outlet port 24 spaced inwardly or upwardly from said outer or lower inlet port 22. As disclosed, the inlet and outlet ports 22 and 24 are at diametrically opposite sides of the pump chamber 17 although this need not necessarily be the relative arrangement of said ports.

A hollow slide valve or sleeve 25 of the dispenser, of cylindrical configuration as shown, is mounted within the pump chamber 17 for free reciprocatory movement longitudinally of said pump chamber, and a pump plunger 26, also of cylindrical configuration in the disclosure as made, is mounted within the hollow slide valve or sleeve 25 in such manner that at some times during operation of the dispenser said pump plunger 26 will be given longitudinal movement in the pump chamber as a unit with said hollow slide valve or sleeve and at other times during operation of said dispenser the pump plunger will be given longitudinal movement in said pump chamber relative to the hollow slide valve or sleeve. Stated otherwise, said pump plunger 26 is snugly mounted in the hollow slide valve or sleeve 25 to be frictionally slidable in said hollow slide valve or sleeve and the hollow slide valve or sleeve is snugly mounted within the pump chamber 17 to be freely slidable in said pump chamber. An operating piece or head upon the pump plunger 26, situated at the outer or upper side of the body portion 11 at the location of the concavity 20, is indicated 27, and a coil spring 28, in surrounding relation to said pump plunger 26 between an inner surface of the operating piece or head 27 and the base wall 21 of said concavity 20, is adapted normally to urge the pump plunger outwardly or upwardly of the pump chamber 17.

An elongated slot in an upper portion of the hollow slide valve or sleeve 25 is denoted 29, an outlet port in a lower portion of said hollow slide valve or sleeve is represented 30, and an elongated slot in an upper portion of the pump plunger 26 is designated 31. A stop piece or peg 32 has its exterior end portion fixedly located in an upper portion of the wall of the extension portion 16 and its interior end portion situated within the elongated slots 29 and 31 in said hollow slide valve or sleeve 25 and said pump plunger 26, respectively.

The construction and arrangement will be such that outward or upward movement of the pump plunger 26 will be arrested by engagement of an inner or lower limiting surface 33 of said pump plunger, defining the inner or lower end of the elongated slot 31, with the stop piece or peg 32 and that inward or downward movement of the pump plunger will be arrested by engagement of an outer or upper limiting surface 34 of said pump plunger, defining the outer or upper end of said elongated slot 31, with said stop piece or peg 32. The construction and arrangement also will be such that outward or upward movement of the hollow slide valve or sleeve 25 will be arrested by engagement of an inner or lower limiting surface 35 of said hollow slide valve or sleeve, defining the inner or lower end of the elongated slot 29, with the stop piece or peg 32 and that inward or downward movement of the hollow slide valve or

sleeve will be arrested by engagement of the outer or lower end of said hollow slide valve or sleeve with the transverse closure wall 18. The outer or lower end or edge 36 of the hollow slide valve or sleeve 25 is in perpendicular relation to the longitudinal axis of said hollow slide valve or sleeve and in parallel relation to the internal surface of said transverse closure wall 18, and when the outer or lower end or edge of the hollow slide valve or sleeve is seated against said internal surface of the transverse closure wall 18, an interior space within said hollow slide valve or sleeve adjacent the outer end of or below the pump plunger 26 will be sealed off from the inlet port 22. Also, when the hollow slide valve or sleeve 25 is situated so that its outer or lower end is seated against the interior surface of the transverse closure wall 18, the outlet port 30 of said hollow slide valve or sleeve will be aligned with the outlet port 24 in the extension portion 16 in communicating relation with the discharge outlet 23. It is the function of the stop piece or peg 32 additionally to preclude rotative movement of the hollow slide valve or sleeve 25 in the elongated pump chamber 17 to insure that the outlet ports 30 and 24 constantly will lie in a plane passed longitudinally through the extension portion 16. Stated otherwise, it is necessary that the outlet port 30 constantly be set relative to the outlet port 24 so that said outlet ports will be aligned when the hollow slide valve or sleeve 25 is at its innermost position, and in the disclosure as made the stop piece or peg 32 constitutes means for retaining said hollow slide valve or sleeve against movement of rotation thus to insure alignment of said outlet ports 24 and 30.

In Fig. 1 of the drawing, the pump plunger 26 and the hollow slide valve or sleeve 25 are disclosed as when retained at their outermost or uppermost positions by the coil spring 28, the limiting surface 33 of said pump plunger and the limiting surface 35 of said hollow slide valve or sleeve being engaged against the stop piece or peg 32. Assuming that liquid substance in the bottle 15 also fills the lower portions of the pump chamber 17 and the hollow slide valve or sleeve 25 beneath the pump plunger 26 and said pump plunger manually to be depressed, against resilient action of the coil spring 28, the pump plunger and said hollow slide valve or sleeve initially will be moved inwardly or downwardly of the bottle together as a unit until the outer or lower end of the hollow slide valve or sleeve has engaged the interior surface of the transverse closure wall 18. During this initial inward or downward movement of said pump plunger and the hollow slide valve or sleeve, liquid substance will be pushed backwardly to an unimportant extent through the inlet port 22 into the interior of said bottle.

In Fig. 2 the pump plunger and the hollow slide valve or sleeve are disclosed situated as when said pump plunger manually has been pushed inwardly to extent just sufficient to cause the outer or lower end of said hollow slide valve or sleeve to be engaged against the interior surface of the transverse closure wall 18, the inlet port 22 to be closed to passage of liquid substance backwardly through said inlet port, and the outlet ports 30 and 24 to be aligned. Of course, inward movement of the hollow slide valve or sleeve 25 could be arrested by engagement of the outer or upper limiting surface of the elongated slot 29 with the stop piece or peg 32 after the outlet ports 30 and 24 have become aligned and the inlet port 22 has been shut off by the outer or lower end portion of

said hollow slide valve or sleeve in response to inward movement of the hollow slide valve or sleeve, instead of by engagement of the outer or lower end of said hollow slide valve or sleeve with the transverse closure wall 18, as will be understood. Supposing the pump plunger and the hollow slide valve or sleeve to be situated as in said Fig. 2, or as when movement inwardly of the bottle of said hollow slide valve or sleeve has just been arrested by engagement of the outer or upper limiting surface of the elongated slot 29 with the stop piece or peg 32, and manual depression of said pump plunger to be continued, the pump plunger will be moved inwardly or downwardly of the bottle relative to the hollow slide valve or sleeve thus to cause liquid substance to be emitted from the discharge outlet 23 by way of said outlet ports 30 and 24.

In Fig. 3 the pump plunger and the hollow slide valve or sleeve are disclosed as when said pump plunger has been pushed inwardly of the bottle to its extreme extent so that the upper limiting surface 34 of the elongated slot 31 is engaged with the stop piece or peg 32 while said hollow slide valve or sleeve also is at its extreme inner position. Supposing the pump plunger when situated as in said Fig. 3 to be released, said pump plunger and the hollow slide valve or sleeve initially will be moved outwardly or upwardly of the bottle together as a unit, in response to resilient action of the compression coil spring 28, until the inner or lower limiting surface 35 of the elongated slot 29 of the hollow slide valve or sleeve has engaged the stop piece or peg 32. During this initial outward or upward movement of said pump plunger and said hollow slide valve or sleeve, liquid substance will be permitted to enter the interior space within the hollow slide valve or sleeve adjacent the outer or lower end of said pump plunger by way of the inlet port 22, and at the same time the outlet port 30 will be moved out of alignment with the outlet port 24.

In Fig. 4 the pump plunger and the hollow slide valve or sleeve are disclosed situated as when said pump plunger has been moved outwardly by the compression coil spring 28 to extent just sufficient to cause the inner or lower limiting surface 35 of said hollow slide valve to be engaged against the stop piece or peg 32. As shown in said Fig. 4, the inlet port 22 is open to the interior of the lower portion of the pump chamber 17 and the outlet port 30 is out of communication with the outlet port 24. Supposing the pump plunger and the hollow slide valve or sleeve to be situated as in Fig. 4 and outward movement of said pump plunger by the compression coil spring 28 to be continued until the parts are situated as disclosed in Fig. 1, the pump plunger will be moved outwardly or upwardly of the bottle relative to the hollow slide valve or sleeve thus to cause liquid substance to be drawn or sucked through the inlet port 22 into the outer or lower portions of the pump chamber 17 and the hollow slide valve or sleeve 25.

It will be obvious that the dispenser as illustrated and described can be manipulated to cause measured amounts of a liquid substance to be dispensed from a container such as the bottle 15. With each outward movement of the pump plunger 26, adapted to be accomplished by resilient action of the compression coil spring 28, a measured quantity of the liquid substance will be loaded into the dispensing device, and

with each inward movement of said pump plunger, adapted manually to be accomplished, a measured quantity of the liquid substance will be removed from said dispensing device. The discharging operations will occur with movement of the parts of the dispenser from their positions as in Fig. 1 through their positions as in Fig. 2 to their positions as in Fig. 3, and the re-loading operations will occur with movement of the parts of said dispenser from their positions as in said Fig. 3 through their positions as in Fig. 4 to their positions as in said Fig. 1.

What is claimed is:

1. A liquid substance dispensing device comprising a hollow casing providing a pump chamber open at one of its ends and closed at its opposite end, a hollow slide valve mounted in said pump chamber for movement longitudinally of the pump chamber, a pump plunger 15 mounted in said hollow slide valve for frictional movement longitudinally of the hollow slide valve, said hollow casing including an inlet port opening to said pump chamber at a location adjacent its closed end and an outlet port leading from the pump chamber at a location spaced inwardly of said inlet port, and said hollow slide valve including an outlet port adapted selectively to be situated in and out of alignment with said outlet port of said hollow casing, each of said hollow slide valve and said pump plunger including an elongated slot, the slot in said pump plunger being longer than the slot in said hollow slide valve and means including a stop piece having an exterior portion thereof fixed in said hollow casing and an interior end portion thereof situated within the elongated slots of the hollow slide valve and the pump plunger for limiting the extent of longitudinal movement of both said hollow slide valve and said pump plunger the difference in the lengths of said slots in said pump plunger and hollow slide valve permitting longitudinal movement of the pump plunger outwardly of the hollow slide valve after movement of said hollow slide valve has been arrested.
2. A liquid substance dispensing device comprising a hollow casing providing a pump chamber open at one of its ends and closed at its opposite end, a hollow slide valve mounted in said pump chamber for free movement of reciprocation longitudinally of the pump chamber in direction toward and away from the closed end of said pump chamber, a pump plunger snugly mounted in said hollow slide valve for frictional movement of reciprocation longitudinally of the hollow slide valve in direction toward and away from said closed end of the pump chamber, said hollow casing including an inlet port opening to a portion of said pump chamber at a location adjacent its closed end and an outlet port leading from the pump chamber at a location spaced inwardly of said inlet port, said hollow slide valve including an outlet port adapted selectively to be situated in and out of alignment with said outlet port of said hollow casing and said pump plunger being adapted to be manipulated selectively to cause said inlet port to be in communication with an interior portion of said hollow slide valve open to said pump plunger while the outlet ports of said hollow casing and hollow slide valve are out of alignment and shut off from said interior portion of the hollow slide valve open to the pump plunger while said outlet ports of said hollow casing and hollow slide valve are in alignment, each of said hollow slide valve and said pump

plunger including an elongated slot, the slot in said pump plunger being longer than the slot in said hollow slide valve and means including a stop piece having an exterior end portion thereof fixed in said hollow casing and an interior end portion thereof situated within the elongated slots of the hollow slide valve and the pump plunger for limiting the extent of longitudinal movement of both said hollow slide valve and said pump plunger the difference in the lengths of said slots in said pump plunger and hollow slide valve permitting longitudinal movement of the pump plunger outwardly of the hollow slide valve after movement of said hollow slide valve has been arrested.

3. A liquid substance dispensing device comprising a hollow casing providing a pump chamber open at one of its ends and closed at its opposite end, a hollow slide valve mounted in said pump chamber for free movement of reciprocation longitudinally of the pump chamber in direction toward and away from the closed end of the pump chamber, a pump plunger snugly mounted in said hollow slide valve for frictional movement of reciprocation longitudinally of the hollow slide valve in direction toward and away from said closed end of the pump chamber, said hollow casing including an inlet port opening to a portion of said pump chamber at a location adjacent its closed end and an outlet port leading from the pump chamber at a location spaced inwardly of said inlet port, said hollow slide valve including an outlet port adapted selectively to be situated in and out of alinement with said outlet port of said hollow casing and said pump plunger being adapted to be manipulated selectively to cause said inlet port to be in communication with an interior portion of said hollow slide valve open to said pump plunger in response to outward movement of the pump plunger while the outlet ports of said hollow casing and hollow slide valve are out of alinement and shut off from said interior portion of the hollow slide valve open to the pump plunger in response to inward movement of said pump plunger while said outlet ports of said hollow casing and hollow slide valve are in alinement, each of said hollow slide valve and said pump plunger including an elongated slot, the slot in said pump plunger being longer than the slot in said hollow slide valve and means including a stop piece having an exterior portion thereof fixed in said hollow casing and an interior portion thereof situated within the elongated slots of the hollow slide valve and the pump plunger for limiting the extent of longitudinal movement of both said hollow slide valve and said pump plunger, the difference in the lengths of said slots in said pump plunger and hollow slide valve permitting reciprocation of said pump plunger both inwardly and outwardly of said hollow slide valve after movement of the hollow slide valve has been arrested.

4. A liquid substance dispensing device comprising a hollow casing including a body portion adapted to be secured upon a container and an extension portion adapted to be situated within said container, said body portion and extension portion providing a pump chamber open at its outer end and closed at its inner end, a hollow slide valve mounted in said pump chamber for movement longitudinally of the pump chamber,

a pump plunger mounted in said hollow slide valve for frictional movement longitudinally of the hollow slide valve, a hand piece upon said pump plunger, said hollow casing including an inlet port opening to said pump chamber at a location adjacent its closed end, an outlet port leading from the pump chamber at a location spaced inwardly of said inlet port and a discharge outlet, and said hollow slide valve including an outlet port adapted selectively to be situated in and out of alinement with said outlet port of said hollow casing, a compression coil spring for normally urging said pump plunger outwardly of said pump chamber, each 10 of said hollow slide valve and said pump plunger including an elongated slot, the slot in said pump plunger being longer than the slot in said hollow slide valve and means including a stop piece having an exterior portion thereof fixed in said extension portion and an interior portion thereof situated within the elongated slots of the hollow slide valve and the pump plunger for limiting the extent of longitudinal reciprocation of both said hollow slide valve and said pump plunger the difference in the lengths of said slots in said 15 pump plunger and hollow slide valve permitting reciprocation of said pump plunger both inwardly and outwardly of said hollow slide valve after movement of the hollow slide valve has been arrested.

5. A liquid substance dispensing device comprising a hollow casing providing a pump chamber open at one of its ends and closed at its opposite end, a hollow slide valve mounted in said pump chamber for movement longitudinally of the pump chamber and including an elongated slot, a pump plunger mounted in said hollow slide valve for frictional movement longitudinally of the hollow slide valve and including an elongated slot, the slot in said pump plunger being longer than the slot in said hollow slide valve, said hollow casing including an inlet port opening to said pump chamber at a location adjacent its closed end and an outlet port leading from the pump chamber at a location spaced inwardly of said inlet port, and said hollow slide valve including an outlet port adapted 20 selectively to be situated in and out of alinement with said outlet port of said hollow casing, and means rigid with said hollow casing including a stop piece situated in the elongated slots of the pump plunger and hollow slide valve for limiting the extent of longitudinal reciprocatory movement of both said hollow slide valve and said pump plunger, the difference in the lengths of the slots in said pump plunger and hollow slide valve permitting reciprocation of the pump plunger both inwardly and outwardly of the hollow slide valve after movement of said hollow slide valve has been arrested.
